UNITED STATES PATENT OFFICE.

EDWARD J. HORN, OF ROYAL OAK, AND FREDERICK LINDHORST, OF DETROIT, MICHIGAN, ASSIGNEES TO DETROIT TORCH & MANUFACTURING CO., OF DETROIT, MICHIGAN, A CORPORATION OF MICHIGAN.

TORCH.

1,275,260.

Specification of Letters Patent. Patented Aug. 13, 1918.

Application filed March 14, 1918. Serial No. 222,408.

To all whom it may concern:

Be it known that we, EDWARD J. HORN and FREDERICK LINDHORST, citizens of the United States, residing at Royal Oak and Detroit, respectively, in the counties of Oakland and Wayne and State of Michigan, have invented a new and useful Improvement in Torches, of which the following is a specification.

10 This invention relates to blow-torches, especially that type of blow-torch in which a pump is used to compress air in the reservoir that contains the fuel. Torches of this character are not broadly new but we believe that we have designed an improvement in the construction of the torch so as to furnish a very much better support for the burner and so as to avoid a very great fault and annoyance in connection with instruments of this character. It is found that the filled joint between the nut on the burner stem and the reservoir top, which is usually a soldered joint, frequently breaks and requires repair, for obviously no matter how small the break it impairs the operation of the instrument by allowing the compressed air to escape.

20 It is the object of our invention to avoid this breakage of this joint. This we do in the simple way hereinafter described.

25 In the drawings.—

Figure 1 is a side elevation partly in section of the torch.

30 Fig. 2 is a perspective of the reinforcing bridge.

Fig. 3 is an enlarged detail of the joint between the stem of the torch and the reservoir.

35 The reservoir is designated *a* and is provided with a suitable base *b* and a coiled wire handle *c*. The usual pump *d* that passes through the top of the reservoir operates in the usual way. *e* represents a priming pan. *f* is the perforated sleeve or barrel that forms the mixing chamber, *h* and *i* are soldering iron supports and *j* is the valve stem. The barrel, valve, and a neck portion that depends from the barrel, constitute the burner.

40 50 In reciprocating the pump plunger stem up and down through the top of the reservoir the top of the reservoir is bound to warp in and out to a certain extent. Such a warping action is, of course, bound to pull

the solder loose between the nut *k* and the top *p* of the reservoir. The soldered joint is shown at *m* in Fig. 3.

To protect this joint and to more stably support the burner we have provided a reinforcing bridge which extends substantially from the side of the reservoir where the stem of the burner enters to the opposite side. This bridge is securely anchored to the side adjacent the stem by means of a lip *n* that extends down from the beam portion *o* of the bridge or reinforcing member. The opposite end of the bridge fits in between the nut *x*, which secures the handle *y* in place and the top. Between the nut and the side wall is a reinforcing plate *z*. The nut, plate, bridge end and walls of the reservoir are all soldered together, forming a secure anchor for this end of the bridge.

Intervening between the beam portion and the lip *n* is an enlargement which has a threaded hole through it through which the stem of the burner screws.

The lip *n* of this bridge or reinforcing member is soldered to the side of the can or reservoir and the stem of the burner threaded through the bridge. The beam of the bridge is soldered to the top of the reservoir. The stem of the burner passing through the bridge secures the location of the nut *k* just above the bridge and consequently the top of the can is pinched in between the nut and the bridge and there can be no relative movement between these two members so as to tend to break the soldered joint.

45 50 A very important condition that results from this bridge arrangement is that the warping action of the top is substantially prevented by reason of the long lip *n* which runs down and abuts against the side of the can or reservoir *a*. This causes the tubular side wall to resist any warping tendency of the top for obviously with the lip abutting along the inside of the side wall and soldered thereto, any warping tendency of the top as a whole is resisted by the strong tubular side wall. It is well known that there is very little warping tendency in a tubular construction, no matter how thin.

55 60 From the above description it is apparent that not only is a stronger reservoir construction secured but by reinforcing the top with a bridge having a long anchorage to the side wall, any warping strains are trans-

ferred to and resisted by the tubular side wall. Hence the filled or soldered joint between the nut and the top of the reservoir is protected from the tearing stresses due to 5 warping and it is also in connection with the adjacent portion of the top pinched to the reinforcing member itself so that relative movement and disruption of the joint is almost impossible. Furthermore, the 10 burner is supported in stable upright position with respect to the reservoir.

What we claim is:

1. In a torch for the purpose specified, the combination of a tubular reservoir, a 15 stem passing through the top of the reservoir and having a joint with the top of the reservoir in which is included a filled connection, and a reinforcing bridge having a beam portion adapted to lie under the top 20 and a lip portion adapted to extend along the tubular side wall of the reservoir, for the purpose specified.
2. In a torch for the purpose specified, the combination of a tubular reservoir, a

burner stem passing through the top of the 25 reservoir, and a reinforcing bridge having a beam-like portion adapted to underlie the top of the reservoir and having an enlarged portion provided with a threaded opening 30 into which the stem of the burner is threaded and having a lip extending along the tubular side wall of the reservoir.

3. In a torch for the purpose specified, the combination of a burner, a tubular reservoir provided with a top, a stem passing 35 through the top of the reservoir and supporting the burner, and a reinforcing member through which the stem passes having a beam portion adapted to lie against the under side of the top of the reservoir and 40 support the same, and a lip portion adapted to extend along the tubular side wall of the reservoir.

In witness whereof we have hereunto set our hands on the 11th day of March, 1918. 45

EDWARD J. HORN.
FREDERICK LINDHORST.
